(57) **CLAIM**

The ornamental design for a mailbox door assembly, as shown and described.

DESCRIPTION

FIG. 1 is a front elevation view of a mailbox assembly including a door with lock and identification holder and a door frame, showing a first embodiment of our new design.

FIG. 2 is a rear elevation view thereof;

FIG. 3 is a top elevation view thereof;

FIG. 4 is a bottom elevation view thereof;

FIG. 5 is a left side elevation view thereof;

FIG. 6 is a right side elevation view thereof; and,

FIG. 7 is a perspective view thereof, with the door in an open position.
